UNITED STATES PATENT OFFICE.

IVAN ENGSTROM, OF CHICAGO, ILLINOIS, ASSIGNEE, BY MESNE ASSIGNMENTS, TO
CARL M. HEDMAN AND HERBERT R. HEDMAN, BOTH OF CHICAGO, ILLINOIS.

CHECK-PROTECTOR.

1,156,000.

Specification of Letters Patent.

Patented Oct. 5, 1915.

Application filed October 19, 1912. Serial No. 726,674.

To all whom it may concern:

Be it known that I, IVAN ENGSTRÖM, a citizen of the United States, and a resident of the city of Chicago, in the county of Cook and State of Illinois, have invented certain new and useful Improvements in Check-Protectors; and I do hereby declare that the following is a full, clear, and exact description of the same, reference being had to the accompanying drawings, and to the numbers of reference marked thereon, which form a part of this specification.

Of the numerous check protectors heretofore put on the market, but few, if any, have been capable of correctly marking and cutting or indicating on the check (or other evidence of value) the exact money value represented thereby unless said money value should chance to be one of the particular denominations of the few the protector is capable of indicating. Losses have frequently occurred for this reason.

It is an object of this invention to afford a construction in which any desired money value may be correctly expressed, and wherein accuracy is assured by affording at all times a visible indication of the amount or numeral in printing or marking position.

It is an object of the invention to afford a construction, practically all of which may be constructed by means of dies and by stamping, and which admits of exceedingly cheap and economical construction and affords the utmost simplicity and durability.

The invention is illustrated (in a preferred form) in the drawings, and is hereinafter more fully described.

In the drawings, Figure 1 is a side elevation of a machine embodying my invention, showing the same in position to receive a check therebeneath. Fig. 2 is a top plan view thereof. Fig. 3 is a section on line 3 of Fig. 2, showing the machine set and preparatory to actuation to engage the check. Fig. 4 is a similar view, showing the machine in operation marking the check. Fig. 5 is a section on line 5 of Fig. 3. Fig. 6 is a section on line 6 of Fig. 3. Fig. 7 is an enlarged section on line 7 of Fig. 3. Fig. 8 is a section on line 8 of Fig. 6. Fig. 9 is a face view of one of the marking elements, showing the same removed from the machine. Fig. 10 is a fragmentary side elevation, with parts omitted, and showing the operating handle attached directly to the casing. Fig.

11 is a section on line 11 of Fig. 3. Fig. 12 is a type edge view of the marking elements. Fig. 13 is a view of the sliding "limiting" type. Fig. 14 is a face view of the sight indicator for one of said marking elements. 60 Fig. 15 is a face view of the "dollars" type. Fig. 16 is a view illustrating the arrangement of the words and numerals when an impression is made.

As shown in the drawings, 1, indicates a standard or base, as shown constructed of pressed metal, though obviously capable of being made otherwise. At the rear end of said base are provided upwardly directed lugs 2, which may be struck up from the top 70 of the base, as indicated in Fig. 5, and each of which is provided at its rear edge with an upwardly facing shoulder or notch 3. Extending through apertures in said lugs, is a shaft 4, and secured on the outwardly extended ends of said shaft is a casing 5, which may also be constructed of pressed metal, if preferred, and comprises a top portion 6, and rounded front end portions 7, and side plates 8, through the latter of which the ends of said shaft extend. The top plate 6, extends rearwardly and is provided with a lip 9, adapted to engage the upwardly projecting stop or shoulder 3, on said lugs to limit the upward swing of the casing. 80 Wound about said shaft 4, and bearing at one end on the base and at the other bearing upwardly on said casing, are coiled springs 9^a, which act to hold the front end of the casing normally elevated, as shown in Figs. 90 1 and 2.

A shaft 10, extends through said side walls at approximately the center of curvature of the front end of the casing, and journaled thereon at about the middle of the casing, 95 are rotative marking elements 11 to 16 inclusive, though, of course, the number may vary with the size of the denominations to be indicated. Each of said indicating elements is struck or stamped of a sheet of 100 metal to substantially a circular shape, as indicated in Figs. 3, 4, and 9, and is provided with an integral handle 18, which projects through slots in the front end 7, of said casing, and is shaped at its outer end 105 to be engaged by the fingers of the operator. At the rear of said handle, said marking elements are notched or ratcheted to afford teeth 19, having recesses therebetween to receive a detent 20, one of which is pro- 110

vided for each of said marking elements, and whereby the same is held in adjusted position.

Diametrically opposite the teeth 19, numerals from 1 to 0 are marked upon the periphery of the marking element, as indicated at 21, and in the case of the numeral designating the parts of a dollar or the cents, a smaller underlined numeral is used 10 as shown in Fig. 12. Secured on the handle of each of said marking elements, and fitting closely within the casing, is an indicating tape or ribbon 22, preferably metallic, on the face of which is marked the numerals 15 1 to 0 successively, as shown in Fig. 14, the order being identical with that of the type upon the marking edge of the marking element, and the numerals being so arranged upon said tape that the same will appear at 20 a view aperture or slot in the casing indicated by 23, in Fig. 2, so that the numeral on the marking edge of said element that is in position to mark or print, will be correctly indicated by a like numeral at said view aperture.

Supported upon the base is an upright standard 24, which extends through the top of the casing. Within said casing and secured on the shaft 4, is a forwardly extending bracket or arm 25, which extends obliquely upward to near the shaft 10. Downwardly depending links 26, are secured on the shaft 10, within the casing, and pivotally connected therewith at their lower ends, 30 is a link or connecting rod 27, which is fulcrumed near its rear end on the forwardly projecting arm 25, by means of a pivot pin 28. Connected with the rear extremity of said connecting rod 27, is a rod 29, the upper 40 end of which is engaged on the rearwardly directed end 30, of the operating lever 31, which is journaled, as shown, at the top of said standard 24. Also secured on said shaft 10, is an inking pad 32, comprising a 45 strip of metal bent to U shape, and extending beneath the printing elements, and from side to side the machine and provided with integral arms 33, which extend upwardly behind the links 26, and engage on said shaft 50 10, by means of said lever and linking connections. Downward pressure on the handle 31, acts to swing the inking pad across the face of the type and rearwardly, as shown in Fig. 4, to expose said type in printing position.

Seated in the bed in position to receive the impression of the type, is a printing bed or platen, 34, which may be constructed of hard rubber or any suitable material to suitably 60 coat with the printing faces on the marking elements. Extending through said side walls of the casing near the top thereof, and directly above the shaft 10, is a shaft 34^a, and secured thereon and on the shaft 10, 65 are broad depending bars 35, and 36, on one

of which is rigidly engaged the fixed "dollar" type bar 37, and on the other of which is slidably engaged the "limiting" type bar 38. Each of said type bars bears the word which it is designed to print or mark on the 70 check, in raised type thereon.

Secured on the rear side of the bar 36, is a stud 39, having wound theron the coil of a spring, one of the free ends 40, of which extends downwardly and into a slot in the 75 sliding type bar 38, known as the "limiting" type bar. The other end 41, of said spring extends transversely and outwardly toward the side of the machine and passes through the slotted end of a bent lever 42, which is 80 fulcrumed on a shaft 43, extending through the side walls of the casing. Said lever is provided at its lower end with a stud 44, which projects laterally and into a slot in the bracket 25. Each of the marking elements is provided with a notch or recess 45, beyond the numerals marked or printed on the marking edge thereof, said notch being in register with the end of the limiting type bar 38, when the marking elements are at 85 normal.

The operation is as follows: The appropriate keys or levers are actuated on the machine to indicate the dollars, tens, hundreds, and thousands, etc., it is desired to indicate 90 or mark upon the check, and the marking elements having been rotated by means of said levers, are held in said position by the detents 20, which engage in the notched periphery thereof diametrically opposite the 95 marking faces on said elements. Having set the machine correctly, as may be seen by reading through the sight aperture 23, (wherein the various numerals on the 100 respective types connected with the marking elements actuated must indicate the same reading as the reading in marking position on said element) the lever 31, is pressed downwardly, thereby swinging the inking pad away from the marking faces and simultaneously projecting the limiting type bar 38, through the notches 45, behind the marking elements not actuated or required in marking the required amount upon the 105 check. The check is now inserted upon the 110 printing plate and the casing struck downwardly thereupon bringing the top of the marking element thereon to mark the required value. The casing immediately upon being released, is thrown upwardly by the 115 spring 9^a, returning the inking pad to normal position and also the lever 31, retracting the limiting type bar. The keys are 120 now returned to normal preparatory to the next use.

Of course, if desired, it is to be understood that the lever may be secured direct upon the casing, as indicated in Fig. 10, and the operations hereinbefore described may be performed by actuating the casing only. 125 130

I have, however, shown but a preferred form of my invention, and I therefore do not purpose limiting the patent granted on this application otherwise than necessitated by 5 the prior art.

Throughout the claims I have used the word "printing" in its generic sense, meaning thereby any operation of printing, embossing or impressing of the check by which 10 the check may have imprinted upon it the desired amount.

I claim as my invention:

1. A base, a casing hinged thereon at one end, a spring normally supporting the 15 casing, rotative marking elements in said casing, a lever for manual actuation on each marking element, a sight indicator attached to each marking element, a detent for holding said marking elements in adjusted position, a spring impelled limiting type 20 adapted to engage and hold the marking elements not used from movement, an inking pad, and levers controlling the limiting type and inking pad to swing the latter 25 away from the type, and permitting the casing to swing downwardly to printing position.

2. A machine of the class described embracing a pivotally supported casing 30 adapted to be struck down, rotative marking mechanisms therein each appropriated to a single denomination and capable of independent operation, a detent for holding the same in adjusted position, a limiting type 35 acting to lock the marking elements not used from movement, and a spring acting to elevate the casing when struck downwardly in making the impression.

3. In a device of the class described a 40 printing check marking device comprising a base, a casing hingedly supported thereon and containing the marking mechanism and adapted to be struck downwardly in making the impression, means for adjusting the individual marking elements independently, a 45 limiting type acting to lock all marking elements from movement when not used, and resilient means for retracting the same as the machine returns to normal.

50 4. In a machine of the class described adjustable and rotating marking elements having numerals consecutively arranged and on a segment of its periphery, a type bar rigidly secured adjacent the marking element for the lowest denomination, a limiting type bar slidably engaged to be automatically projected against the marking element for the highest denomination at any given actuation, a casing containing said 55 elements, a spring acting normally to hold said casing and mechanism elevated, and means operated by the normal upward swing of the casing to retract said limiting type bar after each actuation.

65 5. In a machine of the class described a

base, a casing hingedly connected therewith at one end, a spring acting to hold the free end of the casing elevated, adjustable marking mechanism in said casing, a platen in the base positioned to receive the impression 70 thereof, an inking pad adapted for actuation across the printing faces of the marking mechanism, a lever for swinging the same away from the printing faces, and a transversely slidable limiting type bar operatively connected to be moved into printing position simultaneously with the withdrawal 75 of the inking pad and prior to the downward swing of the casing to printing position, said spring acting to swing said casing 80 and lever and operating parts to normal simultaneously.

6. In a check protector an oscillatable casing, a rigid base therefor, rotatable type disks in said casing adapted to move therewith, a bracket mounted on said base, a lever pivoted on said bracket, a link connecting said lever and said casing, and an actuating member connected to operate said lever to oscillate said casing. 90

7. In a device of the class described a base, a casing pivoted thereon, a plurality of type disks mounted to rotate in said casing and to move therewith, a bracket mounted on said base, a lever pivoted thereon, a 95 link connected to said lever and to said casing, an actuating arm connected to said lever to cause movement of the casing, and an ink pad pivoted in the casing to swing across the type and pivotally connected to said bracket such that actuation of said casing causes simultaneous movement of said ink pad.

8. In a device of the class described a rigid bracket, a casing pivoted to move relative thereto, levers connected to said casing and said bracket for actuation of the casing, printing mechanism in said casing, and inking means therefor pivoted on said casing and on said bracket to move away from the 100 printing mechanism when the casing is actuated for printing. 110

9. In a check protector, the combination of a base, a casing, printing mechanism in the casing, mechanism for pivoting the casing to the base, a manually-operable printing lever pivoted to the base, and a link independent of said pivoting mechanism pivotally connecting said lever with the casing. 115

10. In a check protector, the combination 120 of a base, a casing pivoted to the base, printing devices in the casing and carried thereby, devices for variably and independently setting said printing devices, manually-operated mechanism for moving the casing toward the base to print a desired amount, a platen carried by said base, an inking device, and levers connecting the inking device and base for moving the inking device 125 from between the printing devices and the 130

platen by motion of the casing during a printing operation.

11. A device of the class described comprising a base, a casing hinged to the base, 5 a spring normally supporting the casing, ordered marking elements in said casing, a lever for manual actuation secured to each marking element, a detent for holding said marking elements in adjusted position, a 10 limiting type adapted to hold and engage the marking elements not used from movement, an inking pad, and mechanism controlling the limiting type and inking pad to swing the latter away from the type, and 15 permitting the casing to swing downwardly to printing position.

12. A device of the class described comprising a pivotally-supported casing adapted to be struck down, marking mechanisms 20 in said casing, each marking mechanism appropriated to a single denomination capable of independent operation, a detent for holding the same in adjusted position, a limiting type acting to lock the marking elements not used from movement, and mechanism 25 acting to elevate the casing when struck downwardly in making an impression.

13. A device of the class described comprising a base, a casing supported thereon, 30

said casing containing a plurality of marking elements and adapted to be struck downwardly in making an impression, means for adjusting the individual marking elements independently, a limiting type acting to lock 35 the marking elements from movement when not used, and means for retracting the same after the machine returns to normal.

14. A machine of the class described comprising ordered marking elements having 40 numerals consecutively arranged thereon, a bar rigidly secured adjacent the marking element for the lowest denomination, a limiting type bar slidably engaged to be automatically projected against the marking 45 element for the highest denomination at any given actuation, a casing containing said elements, means acting normally to hold said casing and mechanism elevated, and means operated by the normal upward swing of 50 the casing to retract said limiting type bar after each actuation.

In testimony whereof I have hereunto subscribed my name in the presence of two subscribing witnesses.

IVAN ENGSTROM.
